(57) **CLAIM**

I claim the ornamental design for a suitcase handle, as shown and described.

DESCRIPTION

FIG. 1 is a perspective view of a suitcase handle according to the present invention shown folded against a surface of the suitcase ;

FIG. 2 is a front view thereof;

FIG. 3 is a back view thereof;

FIG. 4 is a bottom view thereof;

FIG. 5 is a top view thereof;

FIG. 6 is a right side view thereof;

FIG. 7 is a left side view thereof;

FIG. 8 is a perspective view of a suitcase handle shown in the extended position;

FIG. 9 is a front view thereof; and,

FIG. 10 is a right side view thereof, the left side view being the mirror image thereof.

The broken lines showing of luggage are included for the purpose of illustrating environment and forms no part of the claimed design.
